TELEPHONE SYSTEM

Arthur J. Ray, Chicago, Ill., assignor to Automatic Electric Laboratories, Inc., Chicago, Ill., a corporation of Delaware

Application October 21, 1943, Serial No. 507,067

14 Claims. (Cl. 179—18)

The present invention relates to telephone systems in general, but is concerned more particularly with the use of voice amplifier repeaters in telephone connections.

It is the object of the present invention to provide automatic means for including a voice amplifier repeater in certain telephone connections established through the medium of automatic switches.

It is a feature of the present invention to provide a trunk repeater which is utilized in establishing telephone connections which may or may not require voice amplifier apparatus and to determine whether the amplifier is to be included in or excluded from the connection by the operation of the automatic switches involved in the connection.

It is a further feature of the invention to provide a trunk repeater which is selectable over either of two different paths and which controls the inclusion or exclusion of a voice amplifier repeater in the connection, depending upon the path over which the trunk repeater is seized.

It is a still further feature of the invention to provide facilities in a two-way trunk repeater of the above type for repeating supervisory signals in either direction over a connection.

Further features of the invention pertain to the particular arrangement of the circuit elements of the telephone system, whereby the above outlined and additional operating features are attained.

Novel features believed to be characteristic of the invention are set forth with particularity in the appended claims. The invention, together with further objects and features thereof, will best be understood by reference to the following specification, taken in connection with the accompanying drawings, in which Figs. 1 to 3, inclusive, when placed end to end in the order named, illustrate a telephone system having incorporated therein the features of the invention as briefly outlined above.

Referring now more particularly to the operation of the system to set up different types of connections, a call originating on a line terminating in exchange A and intended for a line terminating in exchange C will first be considered. Assuming that a call is routed to the manual operator's position in exchange A, the operator attending this position may forward the call in the usual manner by plugging a cord circuit at her position into a jack terminating the trunk 190. When this trunk is seized in this manner a circuit is completed for energizing the battery feed relay 130 in the automatic exchange

B over a circuit as follows: ground, lower winding of relay 130, winding 173 of the repeating coil RC1, contacts 124 and 113, positive conductor 192 of the trunk line 190 through the cord circuit equipment at the operator's position in exchange A, negative conductor 191 of the trunk line 190, contacts 111 and 122, winding 171 of the repeating coil RC1, upper winding of battery feed relay 130, to battery. Battery feed relay 130 energizes over the above-traced circuit and at contact 132 completes an obvious circuit for energizing the slow-to-release relay 210. At contact 131, relay 130 opens a point in the incomplete circuit for relay 230 and at contact 133 it prepares a point in the circuit of conductor 307 extending to the selector 380 shown in Fig. 3. As a result of the above-traced circuit for relay 210, this relay energizes and at contact 211 prepares a circuit for relay 230; at contact 212 it opens a point in the circuit of the ring-back-tone conductor 196; at contact 214 it disconnects the battery potential through resistance 216 from the test conductor 373; at contact 213 it places direct ground potential upon the test conductor 373 in order to busy the repeater circuit of Figs. 1 and 2 to other switches, such as selector 350, having access thereto; and at contact 215 it completes an obvious circuit for energizing the seizure relay 200.

30 Relay 200 upon energizing, at contacts 201 and 203 disconnects the battery feed relay 240 from windings 183 and 185 of the repeating coil RC2, and at contacts 202 and 204 it substitutes therefor the circuit including resistance 291 and the upper winding of relay 220. As a further result of the energization of relay 200, a circuit is completed at contacts 206 and 207 for energizing the line relay 310 of the associated selector 380 in series with the upper winding of relay 220. The 35 circuit for energizing line relay 310 of selector 380 may be traced from ground, lower winding of line relay 310, contact 304, positive conductor 307, contacts 133 and 207, winding 185 of the repeating coil RC2, contact 204, upper winding 40 of relay 220, resistance 291, contact 202, winding 183 of the repeating coil RC2, contact 206, negative conductor 306, contact 301, upper winding of line relay 310, to battery. Upon energizing, relay 310 prepares the selector 380 to receive impulses dialed by the operator at exchange A.

As a further result of the energization of seizure relay 200, a circuit is completed at contact 205 for energizing the lower winding of relay 220. It will be recalled that in the above-

traced circuit for energizing line relay 310 of the selector 380, the upper winding of relay 220 was included in this circuit and consequently its upper winding is also energized. However, the magnetic flux set up in the upper winding of relay 220 at the present time opposes the magnetic flux set up by the circuit completed over the lower winding of the relay. Since the flux generated in the two windings of the relay oppose each other, relay 220 is prevented from energizing at this time. The repeater circuit disclosed in Figs. 1 and 2 is now in condition to repeat impulses transmitted by the operator at exchange A to the selector 380.

Responsive to the seizure of the trunk lines 190 by the operator at exchange A, relays 130, 200, and 210 in the repeater circuit of Figs. 1 and 2 are energized in the manner described above. As a further result of the seizure of the repeater circuit, the associated selector 380 is seized and the line relay 310 thereof is energized over the previously traced circuit. Selector 380 now causes dial tone to be transmitted to the operator at exchange A to indicate that the selector 380 is in condition to respond to impulses comprising the first digit.

It will be assumed in the present instance that the operator at exchange A manipulates the dial, associated with her cord circuit, to transmit impulses indicative of the digit 5. Upon the first momentary interruption of the loop circuit including the battery feed relay 130, the relay momentarily restores to normal, opening the previously traced circuit for the slow-to-release relay 210 at contact 132, and at contact 131 it completes a circuit from ground, by way of contacts 131 and 211, through the winding of relay 230, to battery. Relay 230 energizes over this circuit and at contact 231 prepares a point in a locking circuit for itself, and at contact 232 it completes a multiple circuit in shunt of the upper winding of relay 220 and winding 183 of the repeating coil RC2 in order to improve impulse transmission to the selector 380. Current flow in the upper winding of relay 220 is not reduced sufficiently when the multiple circuit is completed to cause the relay to energize over the circuit including its lower winding.

Due to the fact that relays 210 and 230 are of the slow-to-release type, the momentary interruptions in their energizing circuits, responsive to the momentary deenergization of relay 130 during impulsing, has no effect upon these relays and they remain operative during impulse transmission. At contact 133, relay 130 interrupts the above-traced loop circuit for line relay 310 in order to repeat the impulse transmitted by the operator at exchange A to the selector 380.

Accordingly, relay 310 follows the momentary interruptions under control of battery feed relay 130 and thereby causes the wipers 320 to 322, inclusive, of the selector 380 to be raised in a vertical direction to a level in its associated banks corresponding to the digit dialled by the operator at exchange A. After the wipers have been raised to the desired level they are automatically rotated over the bank contact in search of an idle trunk line terminated in the selected level.

After the last impulse of the series of impulses constituting the digit 5 has been transmitted, relay 130 comes to rest in its energized position and again opens the circuit at contact 131 of the slow-to-release relay 230. At contact 132, relay 130 again closes the circuit of relay 210, and at contact 133 it again completes the loop circuit ex-

10 tending to the selector 380 in order to maintain line relay 310 in its energized condition. Relay 230 subsequently deenergizes and removes the multiple circuit including resistance 290 from the upper winding of relay 220 and the winding 183 of the repeating coil RC2.

15 The selector 380 of Fig. 3 is of the conventional Strowger type and includes a wiper shaft carrying the wipers 320 to 322, inclusive, and an associated set of bank contacts. The wiper shaft is adapted to be operated step by step in a vertical direction to position two wipers opposite one of the 10 levels in the associated bank, which level corresponds to the digit received by the selector. Furthermore, the wiper set is adapted to be automatically rotated over the ten individual spaced contacts in any selector level. Since the Strowger type switch is well known in the art, it has been schematically shown and only such apparatus as is deemed necessary in carrying out the present invention has been shown. More particularly, the normal post springs, NPS including the contact 315, are so positioned that when the wiper shaft is operated to the 10th level the contact 315 is closed and remains closed during the time the wipers 320 to 322, inclusive, remain in any position on the 10th level. It should be noted, however, that the normal post springs NPS may be mounted to be actuated on any desired level and that any number of sets of normal post springs may be provided in order to accomplish the switch operation to be described hereinafter on any one or more levels of the associated set of contact banks.

20 In the present example, at the conclusion of the transmission of the digit 5, the wipers 320 to 322, inclusive, occupy a position adjacent the 5th level in the associated contact bank and shortly thereafter the wipers are automatically rotated over the individual contacts in the 5th level of the bank in search of an idle trunk line extending to exchange C. It will be assumed that the trunk line 340 is idle and that the wipers 320 to 322, inclusive, come to rest in engagement with bank contacts 331 to 333, inclusive, terminating the conductors 334 to 336, inclusive, which are individual to the repeater 330 and the associated trunk line 340. When the test wiper 322 of the selector 380 encounters the bank contact 333 the rotary stepping action of the wipers 320 to 322, inclusive, is terminated and the switch through relay 300 is energized, in the well known manner, to extend the conductors 306 and 307 by way of contacts 302 and 303, wipers 320 and 321, and bank contacts 331 and 332 to the line conductor 334 and 336 extending to the repeater 330.

25 When the repeater 330 is seized over the above-traced circuit it operates to cause ringing current to be transmitted over the conductors 341 and 342 of the trunk line 340 to signal the operator at exchange C and at the same time it functions to transmit a ring back tone signal over the calling end of the connection to indicate to the operator at exchange A that the connection has been extended and that the operator at exchange C is being signalled. The repeater 330 also operates to return ground potential over the test conductor 335 to maintain selector 380 in its operated position and to mark the repeater 330 busy to all other selectors, such as 390, having access thereto.

30 When the operator at exchange C answers the call, the repeater 330 functions to reverse the current flow over the circuit including conductors 334 and 336, 305 and 307, windings 183 and

185 of the repeating coil RC2 and the upper winding of relay 220. It has been pointed out above that the current flow in the circuits through the upper and lower windings of the relay 220 is in such a direction that the relay failed to operate. However, due to the fact that the current flow through the upper winding of relay 220 is reversed when the operator at exchange C answers the call, the current flow through the upper winding of relay 220 is in the same direction as the current flow through the lower winding of the relay, and the relay is thereby energized. Upon energizing, relay 220, at contact 221, completes a circuit for energizing the battery reversing relay 120. Upon energizing, relay 120 at contacts 121 and 123 reverses the current flow over trunk 190 by reversing the connection of battery and ground potential, through the upper and lower windings of battery feed relay 130, to the calling trunk 190. As a result of the reversal of current flow over trunk line 190 a signal is given to the operator at exchange A indicating to her that the operator at exchange C has responded to the call. The operator at exchange A may now converse with the operator at exchange C and forward the necessary information as to the destination of the call. The talking circuit between the operator at exchange A and exchange C includes the trunk line 190, contacts 111 and 113, contacts 121 and 123, windings 171 and 173 of the repeating coil RC1 and the battery feed relay 130, the battery feed relay 130 providing the necessary talking current for the calling end of the connection. Voice currents received in the lefthand windings 171 and 173 of the repeating coil RC1 are induced into the righthand windings 174 and 175 of the repeating coil and are extended by way of contacts 161 and 164 to the lefthand windings 181 and 182 of the repeating coil RC2. Voice currents received in the left-hand windings of repeating coil RC2 are induced into the righthand windings 183 and 185 and thereby repeated by way of contacts 205 and 207, contact 133, conductors 306 and 307, contacts 302 and 303, wipers 320 and 321, contacts 331 and 332, conductors 334 and 336, through the repeater 330, conductors 341 and 342 of the trunk line 340, to the operator at exchange C.

When the operator at exchange C has ascertained the number of the called subscriber she inserts her cord circuit into the jack of the wanted subscriber's line and signals the wanted subscriber. When the called subscriber responds, the operator at exchange C operates a key associated with the cord circuit to extend the talking circuit through the cord circuit at her position of switchboard to the called subscriber.

When the operator at exchange A has ascertained that the called subscriber in exchange C has responded to the call, she operates a key associated with her cord circuit to complete the connection between the calling subscriber in exchange A and the called subscriber in exchange C. The connection between the calling subscriber and the called subscriber is completed and they may now converse.

It will be noted that in the above described connections the voice repeater 180, schematically shown in Fig. 1, has been by-passed because the transmission loss in connections established between the subscribers in exchange A and the subscribers in exchange C is not sufficient to warrant the inclusion of a voice amplifier repeater.

It may be necessary at times for the operators

at the switchboards included in the above described connection to signal one another without releasing the established connection. In order to describe the operation of the circuits involved in the established connection in the event that an operator at one exchange recalls the operator at the other exchange, it will be assumed that the operator at exchange A desires to signal the operator at exchange C in order to get her back in on the established connection. By flashing a key associated with the cord circuit involved in the connection, the operator at exchange A causes the circuit of relay 130 to be momentarily opened and closed a number of times. Each time relay 130 restores to normal a circuit is completed for energizing slow-to-release 230 at contact 131, and at contact 133 the loop circuit including conductors 306 and 307 is opened. In response to the momentary interruptions of the loop circuit including conductors 306 and 307 the repeater 330 functions in the well known manner to cause a flashing supervisory signal to be transmitted to the operator at exchange C to indicate to the operator thereat that the operator at exchange A desires to converse with her. The repeater 330 also maintains ground potential on conductor 335 to prevent the release of selector 380. As a further result of the momentary interruptions in the loop circuit including conductors 306 and 307 the circuit of the upper winding of 220 is also interrupted. However, due to the fact that the circuit through the lower winding is maintained, the relay does not restore at this time. Furthermore, the shunt circuit completed for the upper winding through the circuit including contact 232, responding to the energization of relay 230, and including winding 183 of repeating coil RC2, has a tendency to maintain relay 220 in its energized position. When the operator at exchange C answers the flashing signal the connection between the operators in exchanges A and C is completed and they may converse with one another. When the operators disconnect from the cord circuits the conversational connection between the calling and called subscriber is again completed.

In the event that the operator at exchange C desires to signal the operator at exchange A in order to get the latter operator back in on the established connection, she may do so by momentarily operating a key associated with her cord circuit. In response to the momentary operations of the key, the repeater 330 momentarily reverses the current flow over the loop circuit including conductors 306 and 307 a number of times. Each time the current in the loop circuit is reversed the relay 220 deenergizes due to the fact that the current flow in the upper winding of the relay opposes the current flow through the lower winding of the relay. Each time relay 220 restores to normal it opens the circuit of the reversing relay 120 at contact 221. Each time the circuit of relay 120 is opened the relay restores to normal and at contacts 121 to 124, inclusive, reverses the current flow over the trunk 190. The reversals in current flow over trunk 190 causes the supervisory signal associated with the cord circuit involved in the established connection to flash thereby to indicate to the operator at exchange A that the operator at exchange C desires to converse with her. When the operator at exchange A answers, the connection between the operators is completed and they may converse with each other. After

the conversation is completed the operators disconnect from the established connection and thereby reestablish the conversational connection between the calling and called subscribers.

When the conversation between the subscribers has terminated and the called subscriber hangs up his receiver, the operator at exchange C is thereby given a disconnect signal. In order to breakdown the established connection the operator at exchange C removes the plug of her cord circuit from the trunk 340, thereby causing the repeater 330 to operate and again reverse the current flow over the loop circuit including conductors 306 and 307. Due to the current reversal over conductors 306 and 307, the current flow through the upper winding of relay 220 is again reversed and opposes the current flow through its lower winding. Consequently, relay 220 restores to normal and at contact 221 it opens the energizing circuit of the battery reversing relay 120. Relay 120 restores to normal and at contacts 122 and 124 again reverses the current flow over the trunk 190, thereby giving a disconnect signal to the operator at exchange A. The operator at exchange A may either test the trunk 190 to ascertain whether or not the operator at exchange C is still on the called end of the connection, or she may converse with the calling subscriber in exchange A to ascertain whether or not that subscriber has completed the conversation or desires to extend a new call. Upon ascertaining that the connection is to be disconnected the operator at exchange A removes the cord circuit from the trunk 190, thereby opening the previously traced circuit for maintaining battery feed relay 130 energized. Relay 130 restores to normal and at contact 133 opens loop circuit including conductors 306 and 307 and the selector 380, thereby causing repeater 330 to restore to normal. Repeater 330 in restoring removes the ground potential from the test conductor 335, thereby causing the selector 380 to release and restore its wipers 320 to 322, inclusive, to normal. As a further result of the deenergization of battery feed relay 130, the energizing circuit of release relay 210 is open at contact 132 and at contact 131 it completes a circuit by way of contact 211 for the relay 230. Slow-to-release relay 210 subsequently returns to normal and at contact 213 removes the ground potential from conductor 373, thereby removing the busy condition placed on the trunks 351 and 352, at contact 214 it replaces battery potential, through resistance 216, on conductor 373, thereby indicating to selectors having access to the repeater that the circuit is in condition to be seized. As a further result of the deenergization of relay 210, the circuit of relay 200 is open, which relay upon restoring to normal, connects the battery feed relay 240 by way of contacts 201 and 203 to further prepare the repeater of Figs. 1 and 2 for seizure by way of selectors, such as selector 350. As a further result of the deenergization of relay 200, the energizing circuit for the lower winding of relay 220 is open at contact 205 and at contacts 206 and 207 additional points in the circuit of conductors 306 and 307 are opened. The repeater of Figs. 1 and 2 is now completely restored to normal and is available for new calls.

If the calling party releases the connection first, the operator at exchange A is signalled thereby and responsive to this signal she removes her cord circuit from the trunk 190. When the cord circuit is removed from the trunk 190, re-

lay 130 restores to normal thereby causing the subsequent restoration of relays 210, 200 and 220 in the order named. As a result of the restoration of relay 220, the circuit of relay 120 is opened at contact 221. Relay 120 restores to normal but has no function to perform at this time since the cord circuit at the operator's position at exchange A has been removed from the trunk 190. As a result of the restoration of relays 130 and 220 the loop circuit, including conductors 306 and 307, is opened, thereby causing the repeater 330 to restore to normal. In restoring the repeater 330 reverses the current flow over conductors 341 and 342 and causes a disconnect signal to be given to the operator at exchange C. As a further result of the restoring of repeater 330, ground potential is removed from conductor 335, thereby causing the selector 380 to restore its wipers 320 to 322, inclusive, to normal. The operator at exchange C now removes the cord from the trunk 340 and from the called subscriber's line. The repeater shown in Figs. 1 and 2 is now in condition to be utilized in new calls.

In the above described connection the voice repeater 180 was not required because the transmission loss in connections established between local subscribers in exchange A and local subscribers in exchange C is not sufficient to require the inclusion of a voice amplifier repeater.

In the connection about to be described, it will be assumed that the call received by the operator at exchange A is a toll call from a distant exchange. When a toll call is received by the operator at exchange A for a subscriber in exchange C or for a subscriber in an exchange located beyond exchange C she is required to dial the digit "0" instead of the digit "5," as previously described. The operation of the apparatus as a result of the dialling of the digit "0" causes the voice amplifier repeater 180 to be included in the established connection in order to amplify the speech transmitted over the connection.

More specifically, when a toll call is received by the operator at exchange A she inserts her cord circuit into the trunk line 190, thereby causing the energization of the battery feed relay 130 in the usual manner. At contact 132, relay 130 completes an energizing circuit for the slow-to-release relay 210 and at contact 133 it prepares a point in the loop circuit including conductors 306 and 307. Relay 210, upon energizing, at contact 213 extends ground by way of contact 152 and conductor 373 to mark the repeater busy in the banks of selectors, such as selector 350 having access thereto. As a further result of the energization of relay 210, a circuit is completed at contact 215 for energizing relay 200. Upon energizing, relay 200, at contacts 201 and 203, disconnects relay 240 from the righthand windings of the repeating coil RC2 and at contacts 202 and 204 connects the upper winding of relay 220 in series with resistance 291 to the righthand windings of repeating coil RC2. As a further result of the energization of relay 200, a circuit is completed for the lower winding of relay 220 at contact 205 and at contacts 206 and 207 it completes a loop circuit by way of conductors 306 and 307 for energizing line relay 310 in the selector 380. The circuit for energizing line relay 310 may be traced as follows: ground, lower winding of relay 310, contact 304, conductor 307, contacts 133 and 207, righthand winding 185 of the repeating coil RC2, contact 204, upper winding of relay 220, resistance 291, contact 202, upper righthand wind-

ing 183 of repeating coil RC2, contact 206, conductor 306, contact 301, upper winding of line relay 310 to battery. The current flow through the upper winding of relay 220 opposes the current flow through the lower winding thereof thereby preventing relay 220 from energizing at this time. As a result of the seizure of selector 380 in the above described manner dial tone is transmitted to the operator at exchange A indicating that the connection is established with a selector and that it is in condition to respond to impulses transmitted from the dial associated with the cord circuit at the operator's position.

Since the connection being described is one requiring the inclusion of the voice repeater 180 the operator at exchange A manipulates her dial to transmit impulses indicative of the digit "0." Relay 130 responds to the impulses transmitted in the manner previously described and at contact 133 repeats the received impulses to the selector 380. Upon the first deenergization of the relay 130, a circuit is completed at contact 131 for energizing the slow-to-release relay 230, which relay, upon energizing at contact 232, closes a multiple circuit including resistance 290 across the upper winding of relay 220, resistance 291 and winding 183 of the repeating coil RC2 in order to improve impulse transmission to the selector 380. Relays 210 and 230 remain energized during the time the impulses constituting the digit "0" are being transmitted to the selector 380. After the last impulse of the series is transmitted, relay 130 comes to rest in its energized position, thereby opening the circuit of relay 230 which relay upon restoring removes the multiple circuit including resistance 290 from across the circuit including the upper winding of relay 220, resistance 290 and repeating coil winding 183.

In response to the ten impulses constituting the digit "0," line relay 310 of the selector 380 causes the wipers 320 to 322, inclusive, to be raised in a vertical direction to the 10th level of its associated bank contacts. When the shaft carrying the wipers 320 to 322, inclusive, is raised to the 10th level, the normal post springs, NPS, are operated to close contact 315. Shortly after the wipers of the switch has been raised to the 10th level they are automatically rotated over the individual contacts in the level in search of an idle trunk line extending to a repeater, such as repeater 330. It will be assumed that the wipers 320 to 322, inclusive, have been rotated over the 10th level of its associated bank and have come to rest in engagement with bank contacts 325 to 327, inclusive, terminating conductors 334 to 336, inclusive, of repeater 330.

As a result of the closing of contacts 315 by the normal post springs NPS a circuit is completed from ground, contact 315, conductor 305, winding of relay 270 to battery. Relay 270 energizes over the above traced circuit and at contact 271 prepares a point in the circuit of cut-in relays 140 and 160, which circuit will be completed subsequently to include the voice amplifier repeater 180 in the established talking connection.

As a result of the seizure of conductors 334 to 336, inclusive, by the selector 380, a circuit (not shown) is completed for relay 300 whereby the loop circuit including conductor 306 and 307, is extended by way of conductor 334 and 336 to control the operation of the repeater 330. When the repeater 330 is seized in the above described manner, ringing current is extended by way of conductor 341 and 342 over the trunk 340 to signal

the operator at exchange C. As a further result of the seizure of repeater 330, ground potential is returned by way of conductor 335 to maintain the selector 380 in its operated position.

5 In order to answer the call received over trunk 340 the operator at exchange C inserts the plug of a cord circuit at her position into a jack terminating trunk 340 thereby causing the repeater 330 to reverse the direction of current flow over the loop circuit including conductors 334 and 336 and conductors 306 and 307. Due to the fact that the current flow over the loop circuit, including conductor 306 and 307, is reversed, the current flow through the upper winding of relay 220 is also reversed and is now in such a direction that it aids the current flow through the lower winding of the relay. Relay 220 now operates and at contact 221 completes an energizing circuit for battery reversing relay 120. Relay 120 operates and at contacts 121 and 123 reverses the current flow over trunk 190 to thereby signal the operator at exchange A that the operator at exchange C has answered the call. As a further result of the energization of relay 120 a circuit is completed at contact 125 for operating the cut-in relays 140 and 160 as follows: ground, contacts 213, 152, 125 and 271, windings of relays 160 and 140 to battery. As a result of the energization of relay 140 a circuit is completed at contact 145 for locking relays 140 and 160 in an energized condition independently of the circuit including contact 125 of relay 120. As a further result of the energization of relay 140, contacts 142 and 144 are opened to disconnect the pad circuit, including resistance 176 and condenser 177, from across the terminals 186 and 187 of the voice repeater 180, and at contacts 141 and 143 relay 140 connects terminals 186 and 187, of the voice repeater 180, to the righthand windings 174 and 175 of the repeating coil RC1. As a result of the energization of cut-in relay 160, the pad circuit, including resistance 178 and condenser 179, is disconnected from terminals 188 and 189 of the voice repeater 180 at contacts 163 and 166, and at contacts 162 and 165 the terminals 188 and 189 of the voice repeater 180 are connected to the lefthand windings 181 and 182 of the repeating coil RC2. As a still further result of the energization of relay 160, contacts 161 and 164 are opened to disconnect the circuit normally shunting the voice repeater 180 from the circuit including the righthand windings of the repeating coil RC1 and the lefthand windings of repeating coil RC2.

The operator at exchange A may now converse with the operator at exchange C over a circuit including the voice repeater 180 and informs the operator at exchange C of the number of the wanted subscriber. The operator at exchange C extends the connection to the wanted subscriber's line and after obtaining the wanted subscriber operates a key associated with her cord circuit to disconnect herself from the connection through to the wanted subscriber. When the connection is obtained with the wanted subscriber, the operator at exchange A operates a key associated with her cord circuit to complete the toll connection from the calling subscriber to the called subscriber.

At this time it may be well to mention that if the connection just described was originated by a local subscriber in exchange A and was to be completed to a subscriber in an exchange beyond exchange C the transmission loss would be too great to permit conversation to take place without the inclusion of a voice repeater. The operator at ex-

change A would, therefor, dial the digit "0" instead of the digit "5" in establishing the connection in order to include the voice repeater 180 in the connection in the same manner as has been described above in connection with the toll call received by the operator in exchange A for a subscriber in exchange C.

The operation of the circuits in order to recall the operators at the two exchanges back into the established connection is the same as has been described hereinbefore.

When the conversation between the calling toll subscriber and the local subscriber in exchange C has been terminated the operator at exchange A removes the plug of her cord circuit from the trunk 190 whereupon battery feed relay 130 restores to normal. At contact 133, relay 130 opens the loop circuit including conductor 306 and 307, thereby causing the repeater 330 to transmit a disconnect signal to the operator at exchange A. As a further result of the restoration of relay 130, the circuit of relay 210 is opened at contact 132 whereupon relay 210 slowly restores to normal. Upon deenergizing, relay 210 at contact 213, opens the locking circuit for relays 140 and 160. Relays 140 and 160 restore to normal, thereby reconnecting the pad circuits to terminals 186 and 187 and to terminals 188 and 189 of the voice repeater 180 in order to prevent the voice repeater 180 from oscillating during the period of time it is not included in the talking connection. As a further result of the deenergization of relay 210, the circuit of relay 200 is open at contact 215. Relay 200 restores to normal, thereby opening a further point in the loop circuit extending to the repeater 330 at contacts 206 and 207 and at contacts 201 and 203 it connects the winding of relay 240 to windings 183 and 185 of the repeating coil RC2. At contacts 202 and 204, relay 200 disconnects the circuit including resistance 291 and the upper winding of relay 220 from the repeating coil RC2 and at contact 205 it opens the circuit for the lower winding of relay 220. Relay 220 restores to normal and at contact 221 it opens the circuit of relay 120 which also restores.

As a result of the restoration of relays 120, 130, 140, 160, 200, 210 and 220 the repeater circuit shown in Figs. 1 and 2 is restored to normal. It should be understood that responsive to the restoration of relay 210 the ground potential placed on conductor 373 at contact 213 to make the repeater busy to selectors, such as selector 350, having access thereto is replaced by battery through resistance 216 to mark the repeater idle to such selectors.

Responsive to the opening of the loop circuit including conductors 306 and 307, due to the restoration of relay 130, the repeater 330 restores to normal and thereby removes the holding ground potential from conductor 335. When ground potential is removed from conductor 335 the selector 380 releases and restores its wipers 320 to 321, inclusive, to normal. It should be understood that the repeater 330 and the selector 380 will restore to normal before the repeater of Figs. 1 and 2 have completely restored. As a result of the restoration of the wiper shaft in a vertical direction, the normal post springs, NPS, are restored and contact 315 is opened, thereby causing relay 240 to restore. The equipment is now completely restored to normal and is available for new calls.

If the operator at exchange C should disconnect first, relay 220 would deenergize and thereby cause relay 120 to restore and reverse the current

flow over trunk 190 in the manner previously described to signal the operator at exchange A. Subsequent release of the apparatus being under control of the operator at exchange A as described above.

From the foregoing it should be understood that two classes of connections may be established under control of the operator at exchange A. One class of connection including the voice repeater 180 in the transmission circuit in order to amplify the voice currents transversing the transmission circuit in both direction and the other class of connection excluding the voice repeater 180 from the transmission circuit. Furthermore, it should be understood that the value of the digit dialled by the operator at exchange A in extending the connections determines whether or not the normal post springs, NPS, in the selector 380 will operate and cause the voice repeater 180 to be included in the transmission circuit. The extension of the connection described hereinbefore as a result of dialling the digit "5," did not cause the operation of normal post springs, NPS, and the voice repeater 180 was excluded from the transmission circuit. However, the extension of the connection described hereinbefore as a result of dialling the digit "0" cause the operation of normal post springs, NPS, and the voice repeater was included in the transmission circuit.

A description will now be given of the operation of the system when a call is initiated by a local subscriber in exchange C for a local subscriber in exchange A. When a local subscriber in exchange C initiates a call, the operator at the switchboard thereat answers the call by inserting one end of her cord circuit into the calling line jack and after receiving the number of the called subscriber she inserts the other end of the cord circuit into the jack terminating trunk 340. When the trunk 340 is seized in the above described manner, the repeater 330 operates to extend the conductors 341 and 342 of the calling trunk 340 by way of trunk line 343 to the Strowger type selector 350. As a further result of the seizure of repeater 330, test conductor 335 is grounded in order to busy the repeater 330 in the banks of selectors, such as selector 380, having access thereto. As a result of the seizure of selector 350, dial tone is transmitted back over trunk 343 to the operator at exchange C to indicate that the selector is in condition to receive dialled impulses.

Since the operator at exchange C is aware of the fact that the call to be transmitted is for a local subscriber in exchange A she manipulates the dial associated with the cord circuit at her switchboard to transmit impulses indicative of the digit "8." The selector 350 responds in the well known manner to raise its wipers in a vertical direction to the eight level of its associated set of bank contacts and automatically rotates its wipers over the individual contacts in the eight level in search of an idle trunk line extending to a repeater, such as a repeater disclosed in Figs. 1 and 2. It will be assumed that in the present instance the wipers of the selector 350 have come to rest in engagement with the trunk line 351 comprising the conductors 360, 361, and 362. The idle condition of the trunk line 351 is indicated by the battery potential applied thereto by way of resistance 216, contacts 214 and 152, conductor 373 and conductor 362. When the test wiper of the selector 350 engages 75 the bank contact in its associated set of con-

tacts terminating the conductor 362, a circuit is completed in the selector 350 for extending the loop circuit, including conductors 341 and 342, from the operator's switchboard, through repeater 330, trunk line 343, selector 350, conductors 360 and 361, to the windings of relay 240. The battery feed relay 240 energizes over the loop circuit which may be traced as follows: ground, lower winding of relay 240, contact 263, winding 185 of the repeating coil RC2, contact 265, conductor 374, conductor 361 of trunk line 351, selector 350, trunk line 343, repeater 330, conductor 342 of the trunk line 340, through the operator's cord circuit and returning by way of conductor 341 of the trunk 340, repeater 330, trunk 343, selector 350, conductor 360 of trunk line 351, contact 263, winding 183 of the repeating coil RC2, contact 201, upper winding of the battery feed relay 240, to battery. Relay 240 upon energizing over the above traced circuit, completes a circuit, at contact 242, for energizing relay 150 and at contact 241 it also completes a circuit for energizing the battery reversing relay 120.

Battery reversing relay 120 energizes over the above traced circuit and at contacts 121 and 123 reverses the connection of battery and ground potential through the winding of relay 130 to conductor 191 and 192 of trunk 190. Relay 120 at contact 125 prepares a circuit for the cut-in 25 relays 140 and 160 but this circuit is of no effect since the connection being described does not require the inclusion of the voice repeater 180.

As a result of the energization of relay 150, a circuit is completed by way of contact 155 and 35 258 for grounding the ringing machine start conductor 292 to start the ringing machine in operation. As a further result of the energization of relay 150, ground potential is extended by way of contact 153, conductor 373, and conductor 362 for maintaining the selector 350 and the repeater 330 in operated condition. As a further result of the energization of relay 150, battery through resistance 216 is disconnected from conductor 373 at contact 152. At contact 154, relay 150, upon energizing, completes an energizing circuit for relay 250 in multiple with an energizing circuit for ringing relay 110. At contact 151, relay 150 also connects the ring-back tone conductor 196 by way of condenser 197, contacts 151, 212, 233 and 263 to conductor 360 in order to indicate to the operator at exchange C that the operator at exchange A is being signalled.

Relay 250, upon energizing over the above traced circuit, prepares a locking circuit at contact 251 for relay 230. At contacts 252 relay 250 prepares a circuit for battery reversing relay 260 and at contact 253 it opens a point in the circuit of the deenergized seizure relay 200.

In response to the energization of ringing relay 110, contacts 112 and 114 are closed whereupon direct generator is extended by way of conductor 194, contact 114 and trunk conductor 192 and simultaneously therewith battery potential is extended by way of resistance 193 and contact 112 to trunk conductor 191 for the purpose of signalling the operator at exchange A. As a further result of the energization of relay 110 direct generator connected to conductor 194 is also extended by way of condenser 195 and contact 115 to the upper winding of relay 100. It should be noted that at the time ringing relay 110 connects direct generator to conductor 192 and resistance battery to conductor 191 that at its contacts 111 and 113 it disconnects the battery feed relay 130 from the conductor 191 and 192.

When the direct generator is extended to the upper winding of relay 100, the relay energizes and at contact 101 completes a locking circuit for itself from ground at contact 154. As a further result of the energization of relay 100 the circuit for the slow-to-release ringing relay 110 is opened at contact 102. Relay 110 is made slow-to-release in order to make certain that the direct generator 194 and resistance battery are connected to conductors 192 and 191, respectfully, for a sufficient period of time to signal the operator at exchange A. Ringing relay 110 subsequently restores to normal, thereby opening the signalling circuit at contacts 112 and 114, and extending the conductors 191 and 192 through to the upper and lower windings of the battery feed relay 130 at contacts 111 and 113. As a further result of the deenergization of the ringing relay 110, direct generator is removed from the upper winding of relay 100 at contact 115. No further operations take place in the repeater in exchange B disclosed in Figs. 1 and 2 until the call is answered by the operator at exchange A.

When the operator at exchange A answers a call by inserting one end of her cord circuit into the jack terminating trunk 190 a loop circuit is completed for energizing the battery feed relay 130 as follows: ground, lower winding of relay 130, winding 173 of the repeating coil RC1, contact 123 of the energized battery reversing relay 120, contact 111, conductor 191 of trunk 190 through the cord circuit at the switchboard in exchange A and returning by way of conductor 192 of trunk 190, contact 113, contact 121 of the energized battery reversing relay 120, winding 171 of the repeating coil RC1, upper winding of relay 130 to battery. Relay 130 energizes over the above traced circuit and at contact 132 completes an energizing circuit for the slow-to-release relay 210 in multiple with the battery reversing relay 260. The closing of contact 133 by relay 130 has no function to perform in this type of connection because the circuit extending to the selector 380 is not closed at contacts 206 and 207 of the seizure relay 200.

Responsive to the energization of battery reversing relay 260, contacts 262 and 264 are closed simultaneously with the opening of contacts 263 and 265 whereupon the current flow over conductors 360 and 361 is reversed, thereby causing a signal to be given to the operator at exchange C, indicating that the wanted operator at exchange A has responded to the call. At contact 261, battery reversing relay 260 opens a point in the incomplete locking circuit of relay 230; at contact 266 it prepares a circuit for energizing the cut-in relays 140 and 160 only in the event that relay 280 has previously been energized. Since relay 280 is not energized in this type of a connection the closure of contact 266 has no effect at this time. As a further result of the energization of relay 260, the ringing machine start conductor 292 is opened at contact 268 and at contact 267 a multiple locking circuit is completed for relay 150.

As has been previously pointed out, relay 210 energized responsive to the operation of relay 130. Upon energizing relay 210, at contact 211, prepares a circuit for relay 230, at contact 212 it disconnects the ring-back tone conductor 196 from the calling trunk, and at contact 215 it prepares a point in the circuit of the seizure relay 200. The talking connection between the operator at exchange C and the operator at exchange A is now completed and the conversation may take place whereupon the operator at exchange

A is informed of the telephone number of the wanted local subscriber in exchange A. As a result thereof the operator at exchange A inserts the other end of the cord circuit at her position into the jack of the wanted subscriber's line and when the wanted subscriber answers the call the operator actuates a key in the cord circuit to complete the connection. The operator at exchange C may now actuate a key associated with her cord circuit in order to disconnect herself from the connection and complete the connection between the calling subscriber at exchange C and the called subscriber at exchange A. Transmission battery is fed to the calling end of the trunk by way of the battery feed relay 240 and 15 transmission battery is fed to the called end of the trunk by way of the battery feed relay 130.

The windings of the repeating coils RC1 and RC2 inductively coupling the calling end of the trunk with the called end of the trunk so that conversation may be carried on between the calling and called subscribers.

If the operator at exchange C desires to recall the operator at exchange A she may do so by momentarily operating a flashing key at her position thereby causing the battery feed relay 240 to momentarily deenergize and energize a number of times. Each time relay 240 restores it opens the circuit of battery reversing relay 120, at contact 241. The momentary interruptions of contact 242 has no effect on relay 150 because of the multiple locking circuit therefor completed by way of contact 155 and 267. Each time relay 120 restores it reverses the current flow over trunk 190 at contacts 121 to 124, inclusive, thereby signalling the operator at exchange A. When the operator at exchange A answers the flashing signal caused by the momentary current reversals over trunk 190 she may converse with the operator at exchange C.

In the event that the operator at exchange A desires to recall the operator at exchange C, she may do so by momentarily operating a flashing key at her position, thereby causing the battery feed relay 130 to momentarily deenergize and energize a number of times. Each time the battery feed relay 130 restores it opens the circuit of battery reversing relay 260 and release relay 210 at contact 132 and at contact 131 it completes an energizing circuit for relay 230. Relays 210 and 230 are slow to release relays and do not restore each time the circuit of the relays is opened. Each time battery reversing relay 260 restores it completes a locking circuit for relay 230 at contact 261 and at contacts 262 to 265, inclusive, it reverses the current flow over conductors 360 and 374. Current reversals in the circuit including conductors 360 and 374 causes the repeater 330 to function in the well known manner to transmit a flashing supervisory signal to the operator at exchange C to indicate that the operator at exchange A desires to converse with her. When the operator at exchange C answers the flashing signal conversation between the operators may take place. It should be noted that when the operator at exchange C answered the recall relays 130, 210 and 260 remain in their energized positions and relay 230 subsequently restores to normal.

When the conversation is completed, the operators disconnect from the established connection and thereby reestablish the conversational connection between the calling and called subscribers.

When the conversation between the subscribers is completed they may hang up their receivers.

The replacement of the receiver by the calling subscriber in exchange C causes a supervisory lamp, associated with the cord circuit in the switchboard at exchange C, to give a disconnect signal to the operator. Upon receipt of the disconnect signal the operator at the switchboard in exchange C breaks-down the connection by removing the plugs of the cord circuit from the calling line jack and from the jack terminating the line 340.

Responsive to the removal of the cord circuit from the trunk 340 the repeater 330 functions to open the loop circuit including trunk line 343, the selector 350, the trunk line 350, and talking conductors 360 and 361, whereupon the battery feed relay 240 restores to normal.

As a result of the above described restoration of battery feed relay 240 the circuit for battery reversing relay 120 is opened at contact 241, and at contact 242 a point in the locking circuit of relay 150 is opened, but the latter relay remains locked-up over a circuit including contacts 267 and 155. Relay 120 restores to normal when its circuit is opened and contacts 121 and 123 are opened and simultaneously therewith contacts 122 and 124 are closed, thereby reversing the current flow over the trunk conductors 191 and 192 in order to give a disconnect signal to the operator at the switchboard in exchange A.

Upon receipt of the disconnect signal, the operator at the switchboard in exchange A removes the cord circuit from the jacks terminating the called line and the trunk 190 whereupon battery feed relay 130 deenergizes and restores to normal.

Upon restoring to normal relay 130 completes a circuit for relay 230 at contact 131, at contact 132 it opens a multiple circuit including the windings of release relay 210 and battery reversing relay 260, and at contact 133 it opens a point in the incompletely circuit including conductor 307.

Battery reversing relay 260 restores to normal at this time, but since the calling end of the trunk including conductors 341 and 342 have been disconnected by the operator at exchange C, this relay has no function to perform at this time at contacts 262 to 265, inclusive. At contact 261, however, relay 260, upon restoring completes a circuit from ground, contacts 261, 251, and 231, winding of relay 230 to battery, thereby locking relay 230 in its energized position after it is energized responsive to the restoration of battery feed relay 130. At contact 267 relay 260, upon restoring, opens the locking circuit of relay 150, whereupon relay 150 restores to normal.

Due to its slow-to-release characteristics, relay 210 is somewhat delayed in restoring to normal after its energizing circuit is opened by the restoration of the battery feed relay 130. Subsequently, however, relay 210 restores to normal and at contact 211 opens the initial energizing circuit of relay 230 and at contact 212 it prepares a point in the ring-back tone circuit. At contact 213 relay 210 opens a point in the circuit for applying ground potential to conductor 373, and at contact 214 it prepares a point in the circuit for connecting battery through the resistance 216 to conductor 373.

Relay 150 is a slow-to-release relay and is somewhat delayed in restoring to normal after its locking circuit is opened responsive to the de-energization of the battery reversing relay 260. Subsequently, however, relay 150 restores to normal whereupon a point in the ring-back tone circuit is opened at contact 151, ground potential is removed from the test conductor 373

at contact 153 whereupon the preceding selector switch 350 is caused to release and restore its wipers to normal. In addition, the repeater 330 is released and removes the ground potential from conductor 335 to indicate to selectors, such as 380, that the repeater 330 is available for further use. At contact 154 relay 150 opens the energizing circuit of relay 250 and simultaneously therewith it opens the locking circuit including the lower winding of relay 100 and finally at contact 152 it connects battery through resistance 216 to the test conductor 373 thereby marking the repeater of exchange B (Figs. 1 and 2) available in the banks of selectors, such as selector 350, for additional calls.

Relay 100 restores to normal when its locking circuit is open in the above described manner and at contact 102 again prepares a circuit for the ringing relay 110. Slow-to-release relay 250 subsequently restores to normal after its circuit is opened by the restoration of relay 150, and at contact 251 it opens the locking circuit for relay 230, which relay subsequently restores to normal. At contact 252, relay 250 opens a point in the incomplete circuit of relay 260, and at contact 253 it prepares a point in the incomplete circuit of seizure relay 200. The equipment involved in the connection established between the subscriber at exchange C and the subscriber at exchange A has now completely restored to normal and is available for additional calls.

In the above described operation of the release of the equipment responsive to the termination of the connection it was assumed that the calling subscriber at exchange C restored his receiver first to terminate the connection. It will now be assumed that the established connection previously described between the subscriber at exchange C and the called subscriber at exchange A was terminated by the restoration of the receiver by the called subscriber.

When the called subscriber at exchange A restores his receiver the supervisory lamp associated with the cord circuit at the switchboard in exchange A is illuminated to give the operator the disconnect signal. When the operator at exchange A receives the disconnect signal she removes the plugs of the cord circuit from the calling line and from the jack terminating the trunk 190 whereupon battery feed relay 130 restores to normal. Upon deenergizing, relay 130 completes an energizing circuit for relay 230 by way of contact 131 and the closed contact 211. Upon energizing relay 230 prepares an incomplete locking circuit for itself at contact 231. A further result of the deenergization of relay 130 the multiple circuit including the windings of relays 210 and 260 is opened at contact 132. As a result thereof relay 260 restores to normal and at contact 261 completes the locking circuit for relay 230 by way of contacts 251 and 231. As a further result of the deenergization of relay 260, contacts 262 and 264 are opened and simultaneously therewith contacts 263 and 265 are closed whereupon the current flow over conductors 360 and 374 is reversed, whereupon, through the medium of the repeater 330, a supervisory signal is given to the operator at exchange C indicating that the operator at exchange A has released the connection. As a further result of the deenergization of relay 260 a point in the circuit of the ringing machine start conductor 292 is closed at contact 268.

When the operator at exchange C receives the supervisory signal indicating the release of the connection by the operator at exchange A she

challenges the calling line in order to determine whether or not the calling subscriber has replaced his receiver. Assuming that the calling subscriber requires no further service and hangs up his receiver, the operator at exchange C then removes the cord circuit from the jack of the calling line and from the jack terminating the trunk 340 whereupon the circuit of the battery feed relay 240 is opened and the relay restores to normal in the manner previously described.

Relay 240, upon restoring to normal, at contact 241 opens the circuit of the battery reversing relay 120, and at contact 242 it opens the circuit of the slow-to-release relay 150. Relay 120 restores to normal and at contacts 121 to 124, inclusive, reverses the current flow over conductors 191 and 192, but this operation has no function to perform at this time because the operator at exchange A has removed the cord from the trunk 190. Relay 150 subsequently restores to normal and at contact 153 removes ground potential from the test conductor 373, thereby releasing the selector 350 in the manner previously described. At contact 152 relay 150 again connects battery through the resistance 216 to the test conductor 373 by way of the contact 214 in order to mark the repeater in exchange B (Figs. 1 and 2) available for additional calls. As a further result of the restoration of relay 150, the multiple circuit including the lower winding of relay 100 and relay 250 is opened at contact 154. Relay 100 restores to normal and at contact 102 again prepares a circuit of ringing relay 110. Relay 250 subsequently restores to normal thereby opening the locking circuit of relay 230 at contact 251, and at contact 252 it opens an additional point in the circuit of relay 260, and finally, at contact 253 it prepares a point in the circuit of the seizure relay 200. The equipment involved in the connection established between the calling subscriber at exchange C and the called subscriber at exchange A has now been restored to normal and is available for additional calls.

From the foregoing description it should be understood that when a call originated by a subscriber in exchange C for a local subscriber in exchange A the operator in setting up the connection dials the digit "8" and thereby operates the selector 350 to the eighth level in order to seize the repeater in exchange B (Figs. 1 and 2) over the trunk line 351. When the repeater in exchange B (Figs. 1 and 2) is seized over trunk line 351 the connection established thereover excludes the voice repeater 180. In the event that it is necessary to include the voice repeater 180 in the connection in order to amplify the speech current traversing the connection, the repeater in exchange B may be seized over the trunk line 352 by the selector 350. The operation of the equipment in the establishment of a call requiring the inclusion of the voice repeater 180 will now be described.

It will now be assumed that a local subscriber in exchange C desired to establish a connection with a subscriber in an exchange located beyond the area served by exchange A. When the operator at exchange C ascertains the number of the wanted subscriber she inserts the plug of her cord circuit into the jack terminating the trunk line 340 whereupon the repeater 330 is operated to ground the test conductor 335 and thereby mark the repeater 330 busy in the banks of selectors having access thereto. As a further result of the seizure of repeater 330 a circuit is completed by way of trunk line 343 for operating se-

lector 350. When the operator at exchange C receives the dial tone indication that the selector 350 is in condition to receive dialled impulses she manipulates her dial to transmit impulses indicative of the digit "0".

The selector 350 responds in the well known manner to raise its wipers to the tenth level of its associated bank contacts and to automatically rotate the wipers over the individual contacts in the bank in search of an idle trunk line extending to an idle repeater, such as the repeater in exchange B shown in Figs. 1 and 2. It will be assumed that the wipers of the selector 350 have come to rest on the bank contacts terminating conductors 370 to 372, inclusive, of the trunk 352. The repeater is marked as idle in the bank of the selector 350 by the battery potential applied to the test conductors 373 by way of resistance 216, contacts 214, 152, conductors 373 and 372. When the selector 350 seizes the repeater in the above described manner a loop circuit is completed over the trunk line including the trunk conductors 370 and 371 whereupon the following circuit is completed: ground, lower winding of battery feed relay 240, contact 203, winding 185 of the repeating coil RC2, contact 265, conductor 374, conductor 370 of trunk line 352, selector 350, trunk line 343, repeater 330, conductor 341 of the trunk 340 through the cord circuit at exchange C and returning by way of conductor 342 of the trunk 340, repeater 330, trunk 343, selector 350, conductor 371 of the trunk 352, upper winding of relay 280, contact 263, winding 183 of the repeating coil RC2, contact 201, upper winding of battery feed relay 240 to battery. Relays 240 and 280 energize over the above traced circuit. Upon energizing, relay 240 completes an energizing circuit for battery reversing relay 120 and it completes an energizing circuit for relay 150. Upon energizing battery reverse relay 120 reverses the current flow over the trunk conductors 191 and 192 at contact 121 to 124, inclusive, and at contact 125 it prepares a point in the circuit of the relays 140 and 160. When relay 150 energizes it removes battery through resistance 216 from the test conductor 373 at contact 152 and at contact 153 it places ground potential on the test conductor 373 in order to maintain the selector 350 in its operated position. At contact 151, relay 150 connects the ring-back tone connector 196 to the calling end of the trunk in order to indicate to the operator at exchange C that the operator at exchange A is about to be signalled. As a further result of the energization of relay 150 a circuit is completed at contact 155 for grounding the ringing machine start conductor 292 in order to start the ringing machine apparatus in operation, and at contact 154 it completes a multiple circuit for operating relays 250 and 110.

It will be noted that when ground potential is applied to the test conductor 373, responsive to the closure of contact 153, a locking circuit is completed for the energized relay 280 by way of its contact 282 which contact was the only contact closed when the relay 280 was energized over a circuit including its upper winding. Relay 280 now fully energizes and at contact 281 places a shunt around the circuit including the upper winding of the relay and at contact 283 it prepares a point in the circuit of the cut-in relays 140 and 160.

Relay 250 energizes when its circuit is completed at contact 154 and functions in the manner previously described to prepare circuit at con-

tacts 251 and 252 and to open a point in the circuit of the seizure relay 200 at contact 253.

Ringing relay 110 energizes in the manner previously described and causes the operator at exchange A to be signalled. Direct generator from conductor 194 is also extended by way of condenser 195 and contact 115 to the upper winding of relay 100. Relay 100 energizes from the ringing current transmitted over this circuit thereby completing a locking circuit for its lower winding by way of contact 101 to ground at contact 154, and at contact 102 it opens the energizing circuit of ringing relay 110. The ringing relay 110 is made somewhat slow-to-release to insure the signalling of the operator at exchange A. Relay 110 subsequently restores and disconnects resistance battery and direct generator from the trunk conductors 191 and 192 at contacts 112 and 114, and at contacts 111 and 113 it extends the trunk conductor through to the upper and lower windings of the battery feed relay 130.

The operator at exchange A answers the call in the usual manner, by inserting the plug of a cord circuit into the jack terminating trunk 199 whereupon a circuit is completed for energizing the battery feed relay 130. Upon energizing relay 130 completes a multiple circuit at contact 132 for energizing release relay 210 in multiple with the battery reversing relay 268. Relay 210 energizes and at contact 212 disconnects the ring-back tone conductor 196 from the calling end of the trunk line, and at contact 211 it prepares a point in the circuit of relay 230.

Responsive to the energization of relay 260 current flow over conductors 371 and 374 is reversed by the closing of contacts 262 and 264 and the simultaneous opening of contacts 263 and 265. The reversal of current flow over conductors 371 and 374 causes the repeater 330 to function and transmit a supervisory signal over trunk 340 to indicate to the operator at exchange C that the operator at exchange A has answered the call. As a further result of the energization of relay 230, relays 140 and 160 are energized over the following circuit: ground, contact 153, conductor 173, contacts 266 and 283, windings of relays 160 and 140 to battery. Relays 140 and 160 energize over this circuit and at contact 145 relay 140 completes a locking circuit for both relays in series from ground at contact 153, which circuit is independent of the previously traced circuit including contacts 266 and 283. As a further result of the energization of relay 140 the pad circuit including resistance 176 and condenser 177 is disconnected from the terminals 186 and 187 of the voice repeater 180 at contacts 142 and 144, and simultaneously therewith the terminals 188 and 189 of the voice repeater 180 are connected to the righthand windings of the repeating coil RC1 at contacts 141 and 143. As a result of the energization of relay 160 the pad circuit including resistance 178 and condenser 179 is disconnected from terminal 188 and 189 of the voice repeater 180 at contacts 163 and 166 and simultaneously therewith the terminals 188 and 189 are connected by way of contacts 162 and 165 to the lefthand windings of repeating coil RC2. As a further result of the energization of relay 160 the righthand windings of repeating coil RC1 are disconnected from the lefthand windings of repeating coil RC2 at contacts 161 and 164. The voice repeater 180 is now connected in the talking circuit including the windings of repeating coils RC1 and RC2. Conversation between the operator at exchange C and the operator at exchange A may

now take place in the manner previously described.

Upon ascertaining the number of the wanted subscriber the operator at exchange A extends the connection by way of a subsequent exchange (not shown) and the operator thereat completes the connection to the wanted subscriber in the wanted exchange. The operators included in the connection now release therefrom and conversation between the calling subscriber and the called subscriber may take place with the voice repeater 180 included in the circuit in order to increase the amplification of the voice currents traversing the connection.

The operation of the circuits involved in the connection in order to recall the operators at exchange A and C back into the established connection is the same as has been previously described when a connection is originated by the operator at exchange C.

When the conversation between the calling and called subscriber has been terminated the equipment involved in the connection is released in the manner described hereinbefore, it being noted, however, that the circuit of relay 280 is not opened until ground potential is removed from conductor 373 by the restoration of relay 150.

From the foregoing description it will be understood that the operator in exchange C when originating a call may cause the voice repeater 180 to be included in the connection by operating the selector 350 to the tenth level. Therefore, she is instructed to establish connections by way of the tenth level of selector 350 whenever a local subscriber in exchange C desires to establish a connection with a subscriber in an exchange located beyond the exchange area served by exchange A, or whenever a subscriber located beyond the area served by exchange C initiates a call for a subscriber located either in exchange A or in an exchange beyond the area served by exchange A. Furthermore, the operator at exchange C is instructed to operate the selector 350 to the eighth level whenever a connection is to be established between a local subscriber in exchange C and a local subscriber in exchange A. Accordingly, the voice repeater 180 associated with the repeater of Figs. 1 and 2 will be excluded from the connection established between local subscribers in exchange C and exchange A.

While the present invention has been described and illustrated as applied to a semi-automatic telephone system, it will be understood that various modifications may be made therein to apply the invention to either full automatic or full manual systems and it is intended to cover in the appended claims all such modifications as fall within the true spirit and scope of the invention.

What is claimed is:

1. In a telephone system, an automatic switch, an outgoing trunk line, said trunk line accessible to said switch over a plurality of paths, a repeater associated with said switch, an incoming trunk line terminating in said repeater, means controlled over said incoming trunk for operating said repeater and said switch to complete a connection from said incoming trunk to said outgoing trunk over any of said paths, a voice amplifier, a control circuit effective when operated for including said voice amplifier in said connection, and means in said switch effective in the event said switch is operated to select said out-

going trunk over a particular one of said paths for operating said control circuit.

2. In a telephone system, an incoming and an outgoing trunk line, a trunk circuit terminating said incoming line, an automatic switch having access to said outgoing line over two paths, means for controlling said trunk circuit and said switch for interconnecting said lines to complete a connection therebetween over either of said paths, 10 a voice current repeater, means in said trunk circuit for including said voice current repeater in said connection, and means in said switch for operating said last mentioned means only in the event said switch is operated to select said outgoing trunk over a particular one of said paths.

3. In a telephone system, an incoming and an outgoing trunk line, a trunk circuit terminating said incoming line, an automatic switch having access to said outgoing line over two paths, means 15 for controlling said trunk circuit and said switch for interconnecting said trunk lines to complete a connection therebetween, a voice current amplifier, and means in said switch operated in the event said switch is operated to select said outgoing trunk over one of said paths for controlling said trunk circuit to include said voice current amplifier in said connection.

4. In a telephone system, a first exchange, a tandem exchange, a second exchange, a trunk repeater in said tandem exchange, a trunk line from said first exchange terminating in said repeater, a voice current repeater in said tandem exchange, a switch in said tandem exchange, a trunk terminating in said second exchange accessible to said switch over two paths, means in said trunk repeater controlled from said first exchange for operating said switch to select said second exchange trunk line over either of said paths, and means in said trunk repeater controlled by said switch for associating said voice current repeater with said trunk repeater only in the event said switch is operated to select said second exchange trunk line over a particular one of said paths.

5. In a telephone system, a trunk repeater, a trunk line terminating in said repeater having two incoming branches, an outgoing trunk line also terminating in said repeater, means operated responsive to the seizure of said repeater over either branch of said incoming trunk line for transmitting a signal over said outgoing trunk line, means in said repeater controlled over said outgoing trunk line for transmitting a signal over either of said incoming branches and for completing a talking connection between either of said incoming branches and said outgoing trunk line, a voice amplifier, and means operated only in the event said repeater is seized over a particular one of said incoming branches for operatively connecting said voice amplifier to said talking connection.

6. In a telephone system, an automatic switch, a trunk repeater accessible to said switch over two paths, a voice current amplifier, means in said repeater controlled in one manner in response to the seizure of said repeater over one of said paths for associating said amplifier with said repeater, said means ineffective when said repeater is seized over the other of said paths so that said amplifier is not associated with said repeater.

7. In a telephone system, an incoming trunk line, an outgoing trunk line having a plurality of access paths, switching apparatus controllable 75 over said incoming trunk line for interconnect-

ing said trunk lines over any of said paths, said switching apparatus including a trunk circuit having a plurality of inductively coupled sections, a voice amplifier, means in said trunk circuit effective when operated for including said amplifier in one of said sections, and control means operated in the event said incoming trunk line is interconnected with said outgoing trunk line over a particular one of said access paths for operating said last mentioned means.

8. In a telephone system, a trunk line, a distant exchange terminating said trunk line, said trunk line being utilized for local calls to subscribers in said distant exchange or for toll calls to subscribers located in exchanges beyond the area served by said distant exchange, switching apparatus having access to said trunk line over two paths, means for operating said switching apparatus to seize said trunk line over either of said paths to extend connections over said trunk line to said distant office, a voice amplifier, and means in said switching apparatus operated in the event said trunk line is seized over a particular one of said paths, to extend a toll connection through the medium of said distant office, for including 25 said voice amplifier in said connection, said last mentioned means rendered inoperative in the event said trunk line is seized over the other of said paths to extend a local connection to a subscriber in said distant office.

9. In a telephone system, an incoming trunk line, an outgoing trunk line having two paths of access, a trunk circuit, means for interconnecting said lines including said trunk circuit, a voice amplifier, means in said trunk circuit for including 30 said voice amplifier in said connection operated only in the event said outgoing trunk is selected over a particular one of said paths of access.

10. In a telephone system, a trunk circuit, a voice amplifier, means for establishing a talking circuit through said trunk circuit in either direction, cut-in means for including said amplifier in said talking circuit, a circuit independent of the talking circuit established through said trunk circuit in one direction for operating said cut-in means, and means included in the talking circuit established through said trunk circuit in the opposite direction for controlling said cut-in means.

11. In a telephone system, a trunk circuit, a voice amplifier, an outgoing trunk over which connections are established through said trunk

5 circuit, incoming trunks over which connections are established through said trunk circuit in the opposite direction, cut-in means for including said voice amplifier in the connections established through said trunk circuit, means for controlling the operation of said cut-in means responsive to a connection established over said outgoing trunk, and means included in one of said incoming trunks for operating said cut-in means each time a connection is established 10 through said trunk circuit in said opposite direction over said one incoming trunk.

12. In a telephone system, a trunk circuit, a voice amplifier, means for establishing talking connections including said trunk circuit, means for cutting said amplifier in and out of said talking connections, means operated responsive to a talking connection being established through said trunk circuit in one direction for operating said cut-in means, and other means operated responsive to the establishment of a talking connection through said trunk circuit in the opposite direction for operating said cut-in means.

13. In a telephone system, a two-way trunk circuit, means for establishing telephone connections including said trunk circuit, a two-way voice amplifier, means in said trunk circuit operable to cut said amplifier in and out of said trunk circuit, means operated only in the event a connection is established through said trunk circuit in one direction for controlling the operation of said cut-in means, and means operated only in the event a connection is established through said trunk circuit in the opposite direction for controlling the operation of said cut-in means.

14. In a telephone system, a two-way trunk circuit, means for extending talking connections over the trunk circuit in either direction, a voice amplifier, means for inserting the said amplifier into certain of said talking connections, means for determining whether the amplifier will be inserted into connections extended in one direction dependent upon the one of a plurality of incoming paths over which the trunk circuit is seized, and means for determining whether the amplifier will be inserted into connections extended in the other direction over the trunk circuit dependent upon the one of a plurality of paths over which the connection is extended beyond the trunk circuit.

ARTHUR J. RAY.
